(57) **CLAIM**

The ornamental design for a laser alignment guide, as shown and described.

DESCRIPTION

FIG. 1 shows a perspective view of the laser alignment guide.

FIG. 2 shows an overhead view of the laser alignment guide. FIG. 3 shows an underside view of the laser alignment guide.

FIG. 4 shows a side view of the laser alignment guide.

FIG. 5 shows an opposing side view of the laser alignment guide.

FIG. 6 shows a front view of the laser alignment guide; and, FIG. 7 shows a rear view of the laser alignment guide.

The broken lines shown in the drawings represent environmental effects or potential embodiments and do not form any part of the claimed design.
